CHARLES WALCOTT STRATFORD, OF SAN FRANCISCO, CALIFORNIA

PROCESS AND APPARATUS FOR REFINING OILS

Application filed November 24, 1926. Serial No. 150,488.

This application is a continuation in part, of a prior application Serial No. 54,947, filed September 8th, 1925.

Thereinafter described invention relates to the refining of liquid hydrocarbons, although its principles and benefits may be very advantageously applied in handling other liquid substances in effecting their heating and vaporization. Insomuch as my invention has particularly amongst its purposes the handling of liquid hydrocarbons, I will illustrate and describe its embodiment in the well known type of cylindrical oil still now generally in use in oil refineries.

Among the objects of my invention are, keeping the inner cylindrical surface of the still free from the deposition of solids by causing the liquid hydrocarbon to move rapidly and continuously over the heated surface of the still, increasing the rate of firing of the still by protecting its bottom as exposed to hot furnace gases with a constantly moving liquid mass, increasing the rate of evaporation of the liquid hydrocarbon per unit of heating surface exposed. The accomplishment of these objects enables me to materially increase the capacity or output of the still while protecting its metallic surfaces against overheating, effecting economies not now obtainable in refining oil as charged in volume in a still of this type.

My process is distinguished by the fact that I cause a continuous circulation or stirring of the mass or total volume of oil in the still while simultaneously forcing it to travel at high velocity over the inner heated surface of the still in a rapidly moving sheet while stilling.

This I do by discharging the oil within the still under pressure and with velocity through nozzles against its inner cylindrical surface, a dual movement of the oil in well defined circuits taking place. These two movements of the oil I will term and describe as primary and secondary currents or movements, and I desire it to be understood that the stirring or circulation of the oil in mass and its rapid travel in contact with the inner heated surface of the still is entirely the result of the force of its discharge against the

still surface without the aid of mechanical mixing devices, the primary current spreading the oil into a rapidly moving liquid sheet in contact with the inner still surface and the secondary current mixing it in the mass. The oil may also be said to travel in a thin layer in pressure contact with the inner heated surface of the still while circulating thereover.

The applications of my novel process and apparatus for circulating liquid hydrocarbon in mass within an enclosed heated container, while spreading it in a rapidly moving sheet over the inner heated surface thereof to effect an increased efficiency in its heating and vaporization, will be obvious to those skilled in the art.

The present application has incorporated therein features additional to those shown in the prior application of which this is a continuation in part. The principal object of passing the charged oil over pans prior to its introduction to the oil body in the still, is to cause vaporization of a portion of this oil at a lower mean boiling temperature than would otherwise be the case were the oil immediately mixed with the oil body in the still. The oil body has a materially higher mean boiling temperature than the oil charged. Therefore, if the charging oil is immediately mixed with the oil body in the still, the resulting composite will have a higher mean boiling temperature than with the use of pans, as described.

A further advantage in the method of distributing the charging stock, on its introduction to the still, by passing it over pans having in the bottom thereof a roughened surface which maintains the oil in a constant state of agitation until its discharge into the oil body, thus affording an opportunity for the lighter fractions thereof to be distilled before the liquid oil is combined with the oil body in the still. Furthermore, the present application discloses a means for withdrawing the oil from the system after treatment, which is positive in operation and easily controlled as the draw off line is connected directly into the discharge from the pump which is circulating the oil in the still.

In order that a comprehensive understanding may be had through the illustrative embodiment of my invention herein set out, reference should be made to the accompanying drawings, in which

Fig. 1 is a longitudinal section of a cylindrical oil still with heating furnace of the type now generally employed in refining oil. The still is shown fitted with the apparatus 10 of my invention, which involves in the present setting a centrifugal pump mounted within the still with suction and discharge pipes. The suction of the pump is set to draw the oil from near its bottom and to create a partial vacuum below the surface of the oil level while the discharge of the pump is connected to a pipe manifold with jets or nozzle outlets directed to discharge the oil over and against the bottom of the still.

Fig. 2 is a section taken on line 2—2 in Fig. 1, to show the oil discharge manifold and its nozzles and the relation of the nozzles to the inner cylindrical surface of the still.

Fig. 3 is an enlarged sectional view of one of the nozzles in the manifold showing its discharge opening adjacent the inner surface of the still bottom.

Fig. 4 is a diagrammatic view showing generally how the dual movement of the oil is effected within the still by my process. The primary movement of the oil along the inner surface of the cylindrical still at high velocity is denoted by the full line arrows A, while the secondary movement of the oil within the mass is denoted by the dotted line arrows B. The oil level in the still is denoted by the line X—Y.

The result of this twofold movement is a rapid heat exchange through the still bottom and high rate of vaporization of the oil while stilling.

In this manner I also overcome all undesirable localized overheating of the oil which 45 now takes place in the stills which are charged with oil in volume and which is the cause of deposition of solids therein.

In the drawings, the numeral 1 designates a standard type of enclosed cylindrical container providing an oil still. The still 1 is set over a refractory lined furnace and receives heat against its bottom in the present instance from the hot products of combustion of an oil fire, although heat from any 55 source may be employed so long as the temperature is sufficient to effect the vaporization of the liquid hydrocarbon in the still.

The still 1 is provided with an oil filling inlet 2, controlled by a valve 3. The oil inlet terminates in the still in a Y connection—the separate discharges 2^a and 2^b flowing the oil as it enters the still on to inclined pans or troughs 3^a which are supported in the upper part of the still by brackets 4. In the bottom 65 of these troughs or pans is placed a coarse

wire mesh 5 which serves to keep the oil, during its passage over the pans, in constant motion or in an agitated or rippling condition so that a greater surface of the oil is exposed to the heat of the surrounding vapors in the still. In the bottom of the lower ends of the upper troughs 3^a are apertures which permit the oil to pour down onto the lower inclined troughs 6 where its direction of flow is reversed as shown by the arrows in Fig. 1. These troughs are positioned above the liquid level of the oil contained in the still. After passage over the lower troughs, the films of oil are discharged into the oil body where it receives its ultimate heating. Near the bottom of the still is provided a clean-out line 7 controlled by a valve 8.

The still, as previously suggested, is supported above a furnace 9 preferably heated by means of gas or oil burners diagrammatically shown at 10. The top of the still 1 may be provided with a dome 11 to which the outlet for withdrawing the vapors liberated during the stilling operation is connected. Also the vapor line 11^a may be connected directly to the still. Mounted within the still 1 is a pump 12 and mounted on the exterior of the still is an electric motor 13. Suitable shaft transmission means 14 connects the pump 12 and the motor 13 through the gland and stuffing box 15. The pump 12 is fitted with a suction pipe 16 and the discharge pipe 17. The distributing manifold 17^a comprises an assembly of pipes connected to the pump discharge 17. Headers 18 running laterally of the still 1 and connecting pipes 19 running longitudinally thereof. The headers 18 are so set with reference to the inner surface of the still bottom as to bring the longitudinal pipes 19 into close proximity thereto. Inserted or fitted into the pipes 19, at suitably spaced intervals, are nozzles 20. The nozzles 20 provide a means so that oil pumped through the manifold 17^a will be discharged against the inner surface of the still 1 at a high velocity. The number of nozzles employed is governed by the area of the heated surface over which the oil is discharged, and the intensity desired of the liquid movement desired to be effected.

Again, the rapidly moving liquid over the heated surface being the result of the partial vacuum created by the pump (spread of the oil around the outlets of the jets), it is obvious that with a given oil discharge pressure the spacing of the nozzles over the surface will govern the continuity of the rapidly moving liquid sheet covering formed over the surface. Connected into one end of the manifold 17^a is the discharge line 21—the discharge flow of oil through this line being controlled by a valve 22 positioned just outside of the shell of the still or in any convenient position outside of the still for manipulation by the operator. By means of this valve 22, a con-

stant level may be maintained in the still. A positive discharge flow is assured by the fact that the residual oil is taken directly from the circulating pump discharge. It will be noted that any equivalent form of oil discharge manifold located with nozzles adjacent to the inner still surface may be used without departing from the spirit of the invention.

When it is desired to operate the still, oil is run in through valve 3 and inlet 2 until a quantity suitable for stilling is present. The dotted line X—Y represents generally the surface of such a body of oil. This body of oil is maintained substantially constant in volume by the addition of raw stock through the charging inlet 2 when necessary. When the still is charged it is brought up to any desired temperature. At a predetermined temperature the circulating pump is started and the oil circulated within the still. The pump, creates a vacuum below the level of the oil, and the oil is forced through the discharge manifold 17^a and the jets 20 against the inner heated surface of the still bottom 1, thereby effecting the continuous liquid movement of the process. When the oil has been brought to the desired temperature at which the stilling operation is carried on under the most efficient operating conditions, the still may be operated continuously by the introduction of charging stock through the inlet pipe 2 and the oil level kept constant in the still by a continuous discharge of the residual oil material through the pipe 21 controlled by the valve 22.

The embodiment of my invention herein illustrated and described is for the purposes of setting forth its principles and advantages, and it is understood that the operation is particularly suitable for distillation of oil under so called atmospheric pressure or under reduced pressure conditions, the circulation within the still affording considerably more efficient conditions of operation as to heat transfer than the normal type of shell still operation where the circulation within the oil body is dependent upon convection currents set up by the oil in contact with the heated surface.

It is understood that the apparatus and pipes exposed are heavily insulated to prevent loss of heat by radiation. As mentioned, vapors discharged are taken off from the top of the dome 11 through a vapor pipe 11^a.

While the control of the draw off is shown as a valve 22 in actual commercial practice, this hot residual oil is passed directly from the still through heat exchangers, not shown in the drawings, and the control valve or valves situated on lines through which the cooled oil passes.

Furthermore a liquid level control, not shown, may be employed to automatically

regulate the discharge flow, and thereby control the liquid level in the still.

While the operation is disclosed and described as continuous single still operation, the oil circulation may as well be applied to a battery of stills connected in series so that instead of passing the discharge from the initial still to heat exchangers the oil is introduced into the pans of the next succeeding still. The discharge from the final still of the battery is passed to heat exchange and to storage.

I claim as my invention:

1. An apparatus for refining oil, comprising, in combination, a still adapted to contain a maintained quantity of oil during stilling, circulating means within the still adapted to draw oil from the oil body and means to discharge it under pressure in a plurality of separate streams against the inner heated surface of the still increasing heat exchange and to produce rapid circulation in the oil body, and withdrawal means connected to the circulation means for drawing off treated oil from the body of the still.

2. The process of refining oil in a still containing a maintained quantity of oil during the stilling operation, which comprises continuously drawing the oil from adjacent the heating surface of the still and thereby creating a partial vacuum below the oil level, in discharging the drawn oil in a plurality of separated streams aided by the partial vacuum against the surface under such pressure and in such predetermined relation to each other as to cause each of said streams to form a thin, laterally extending, rapidly moving film of oil against the heated still surface and the several films so formed to mutually coact to induce a rapid circulation of oil upwardly from said heated surface toward the top of the oil body and downwardly to points adjacent the heated still surface, whereby to induce a rapid circulation of the entire body of oil within the still and to cause its repeated contact with the more highly heated portions thereof, and in continuously bleeding a portion of the oil from the system from the discharge of the circulating means.

3. An apparatus for refining oil, comprising in combination, a still, induction and eduction means associated with the still, circulating means within the still, a plurality of connected tubes having jets adjacent the heated surface of the still, said tube system connected with the discharge of the circulating means, a secondary line connected to the discharge line of the circulating means for withdrawing oil from the still and maintaining a constant level therein.

4. A process for refining oil in a still comprising the steps of distilling a maintained quantity therein, continuously drawing oil from the body and discharging the drawn oil in a plurality of separate jets against the

heated still surface, said jets adapted to move the oil over the heated surface in rapidly moving films, and inducing a circulation in the oil body, continuously removing a portion of the oil from the still by bleeding a stream of oil from the tube circulating system, and supplying oil to the body.

5. An oil still comprising a circulating system entirely contained therein operating at relatively higher pressure than the still, an inlet oil supply line and a discharge pipe connected with the pressure circulating system.
